UNITED STATES PATENT OFFICE.

BENJAMIN AUGUSTUS MICHEL, OF NEW ORLEANS, LOUISIANA.

REFRIGERATING APPARATUS.

1,155,363.

Specification of Letters Patent.

Patented Oct. 5, 1915.

Application filed July 13, 1914. Serial No. 850,665.

To all whom it may concern:

Be it known that I, BENJAMIN A. MICHEL, a citizen of the United States, residing at New Orleans, in the parish of Orleans and 5 State of Louisiana, have invented certain new and useful Improvements in Refrigerating Apparatus, of which the following is a specification.

This invention relates to refrigeration apparatus, in which a coil of pipes is employed through which a refrigerant is caused to circulate.

The invention has for its object to provide a simple, inexpensive and highly efficient apparatus of the kind stated, and to this end it consists in a novel combination and arrangement of parts to be hereinafter described and claimed.

In order that the invention may be fully understood, reference is had to the accompanying drawings in which—

Figure 1 is a vertical section of the apparatus; Fig. 2 is a vertical section of a portion of a mixing or churning element; Fig. 3 is an elevation of a drive shaft; Fig. 4 is a section of another position of the mixing or churning element, and Fig. 5 is a section on the line 5—5 of Fig. 1.

Referring specifically to the drawings, V 30 denotes the refrigerator chamber. In the top of this chamber is an opening in which is mounted a cylindrical tank or container A which extends down into the chamber and has at its lower end a contracted portion *a* communicating with the inlet of a centrifugal pump G mounted on the floor of the chamber.

In the container A works a churning or mixing mechanism comprising a cylindrical casing B inclosing a dasher consisting of blades D carried by a tubular shaft U. The outer surface of the casing B is also armed with dasher blades C, and the wall of said casing has perforations O. At the center 45 of the top Q of the casing B is a bearing R through which the dasher shaft U passes. The opening in the top of the chamber V in which the container A seats has a closure *v* which also serves as a closure for the top of the container. The closure has a bushed central opening through which the dasher shaft U passes, the latter terminating on the outside of the closure.

A shaft F passes through the shaft U and 50 extends down to the pump G with which latter it has a driving connection. The shaft

F projects from the upper end of the dasher shaft U, and on said end of the shaft U and the corresponding end of the shaft F are fast bevel gears K and k, respectively. 60 Through the center of the first-mentioned one of said gears the shaft F loosely passes. A bevel gear K' meshes with both of these gears, said bevel gear K' being on a shaft L which is driven by a worm gearing M, N 65 from a suitable source of power. The shaft F is loose in the dasher shaft U, and through the bevel gearing hereinbefore described these shafts rotate in opposite directions. A driving connection between the shaft F 70 and the casing B is provided by a suitable coupling T. On the shaft F is also fast a collar S which supports the lower end of the dasher shaft U. In the center of the bottom of the casing B is an opening P to 75 accommodate the shaft F, said opening being large enough to allow the collar S to clear the same when the parts are assembled.

In the container A, a short distance beneath the casing B, is a screen E having a bearing e at the center for the shaft F.

In the chamber V, at the bottom thereof, is mounted a tank H which is connected to the outlet of the pump G by a conduit h. 80 To this tank is also connected one end of a coil J of pipes, the other end of which is connected to the container A. The conduit h is provided with a drain valve I, and the coil J has an overflow pipe X at the top.

In operation, the casing B is filled with 85 crushed ice, salt, salsoda, muriate of ammonia, or other refrigerants. The space between the casing B and the container A is also filled with a refrigerant. The solution or brine passes through the screen E and down the contracted portion *a* of the container, and upon entering the casing of the pump G it is forced through the conduit h into the tank H, from which latter it enters the coil J and circulates through the same back 90 into the container A. The dasher blades C and D turn in opposite directions and thoroughly agitate the brine. The screen E prevents solid matter from reaching the pump.

By the apparatus hereinbefore described, a very low temperature can be produced in a short time and at a small expense. During business hours, when the chamber V is being frequently opened, the temperature can be 95 kept down by keeping the apparatus in operation, maintaining practically the same 100 105 110

degree of cold and thus preserving the goods in better condition.

I claim:

1. A refrigeration apparatus comprising a chamber, a refrigerant container, a rotatable perforated casing in the container, said casing having dasher blades on the outside, a shaft carrying the casing, a dasher in the casing, said dasher having a hollow shaft through which the first-mentioned shaft extends, means for rotating the shafts in opposite directions, a pump, and a refrigerant circulating coil connected to the outlet of the pump and discharging into the refrigerant container, the inlet of the pump being connected to said refrigerant container.
2. A refrigeration apparatus comprising a chamber, a pump, a refrigerant container having a screen and connected on one side of the screen to the inlet of the pump, a rotatable perforated casing in the container on the other side of the screen, said casing having dasher blades on the outside, a rotary dasher in the casing, means for rotating the casing and the dasher in opposite directions, and a refrigerant circulating coil connected at one end to the pump outlet and at the other end to the refrigerant container.
3. A refrigeration apparatus comprising a chamber, a pump, a refrigerant container connected to the inlet of the pump, a rotatable perforated casing in the container said casing having dasher blades on the outside, a rotary dasher in the casing, means for rotating the casing and the dasher in opposite directions, and a refrigerant circulating coil connected at one end to the pump outlet and at the other end to the refrigerant container.
4. A refrigeration apparatus comprising a chamber, a refrigerant circulating coil in the chamber, a pump discharging into one end of the coil, a refrigerant container into which the other end of the coil discharges, said container being connected to the inlet of the pump, a drive shaft for the pump passing through the container, and refrigerant agitating means carried by that portion of the drive shaft which passes through the container.
5. A refrigeration apparatus comprising a chamber, a refrigerant circulating coil in

the chamber, a pump discharging into one end of the coil, a refrigerant container into which the other end of the coil discharges, 55 said container being connected to the inlet of the pump, and a second container mounted in the first-mentioned container and in communication therewith.

6. A refrigeration apparatus comprising 60 a chamber having a top opening, a refrigerant container mounted in said opening and extending into the chamber, a closure seating in the opening and closing the container, a pump, and a refrigerant circulating 65 coil in the chamber, and having one end connected to the outlet of the pump and the other end to the refrigerant container, the inlet of the pump being connected to said container.

7. A refrigeration apparatus comprising 70 a chamber having a top opening, a refrigerant container mounted in said opening and extending into the chamber, a closure seating in the opening and closing the container, 75 a pump, a refrigerant circulating coil in the chamber, and having one end connected to the outlet of the pump and the other end to the refrigerant container, the inlet of the pump being connected to said container, a 80 drive shaft for the pump passing through the aforesaid closure and the container, and refrigerant agitating means carried by that portion of the shaft which passes through the container.

8. A refrigeration apparatus comprising 85 a chamber, a refrigerant circulating coil in the chamber, a pump discharging into one end of the coil, a refrigerant container into which the other end of the coil discharges, 90 said container being connected to the inlet of the pump, a second container in the first-mentioned container and in communication therewith, said second container having dasher blades on the outside and being rotatable, a rotary dasher in the second container, and means for rotating the dasher and the second container.

In testimony whereof I affix my signature in presence of two witnesses.

BENJAMIN AUGUSTUS MICHEL.
